TRANSLOAD DEVICE

Alan E. Brickman, New Haven, Conn., and Myron E. Capouch, Lakewood, Ohio, assignors to The American Steel and Wire Company of New Jersey, a corporation of New Jersey

Application September 28, 1945, Serial No. 619,158

10 Claims. (Cl. 94—18)

1

This invention relates to a transload device and particularly to such a device for use in an expansion or contraction joint for concrete highways. Various types of transload devices for expansion and contraction joints are in use, but they have various disadvantages, a large part of which are due to difficulties arising in assembling the unit preparatory to pouring the concrete.

It is an object of our invention to provide a transload device for an expansion and contraction joint having means for facilitating assembly of its part.

This and other objects will be more apparent after referring to the following specification and attached drawings, in which:

Figure 1 is an assembled view partly in cross section of the transload device;

Figure 2 is an elevation of the cam support;

Figure 3 is a side elevation of Figure 2;

Figure 4 is a top plan view of the dowel socket;

Figure 5 is a side elevation of the dowel socket of Figure 4;

Figure 6 is a rear view of the dowel socket of Figure 4;

Figure 7 is an elevation of the expansion joint filler;

Figure 8 is a view similar to Figure 1, but showing the invention applied to a contraction joint; and

Figure 9 is a side elevation of the cam support of Figure 8.

Referring more particularly to the drawings, reference numeral 2 indicates the subgrade on which the concrete slabs 4 and 6 rest. Between the slabs 4 and 6 is an expansion joint 8 having a filler 10 which extends substantially the length of the joint. In the case of a road the joint is used as a transverse joint extending the width of the road and the transload device transfers the load from one slab to the next. Resting on the subgrade 2 is an inverted T-shaped support 12 which is formed of a plate bent to form a base 14 and an upright 16 with an opening 18 therein. Fastened to both sides of the upright 16 are spaced apart cam lips 20 and 22. The top cam lip 20 has a downwardly extending flange at each end and the bottom cam lip 22 has similar upwardly extending flanges. The flanges at one side of the upright form cam surfaces 24 and the flanges on the other side form similar cam surfaces 26. Fastened in each slab is a dowel socket 32 which has a barrel portion 34 with an opening 36 therethrough for receiving the dowel pin 38. In order to distribute the load over a greater surface the barrel portion 34 is provided with out-

2

wardly extending bearing surfaces 40 on each side thereof. Flanges 42 extend outwardly from the top and bottom of the barrel portion, and each is provided with a cam surface 44, which cooperate with the cam surfaces 24 and 26 to hold the dowel sockets in place.

In assembling the transload unit, the support 12 is placed on subgrade 2 with the filler 10 supported on the base 14 and extending along the upright 16. A dowel socket 32 is positioned against the upright 16 on the side opposite the filler with the flanges 42 in a horizontal position. The socket is then turned to move the cam surfaces 44 into contact with cam surfaces 26 to lock the socket in place. In like manner, a second socket 32 is positioned against the filler 10 and wedged in place by means of the cam surfaces 24 and 44. A dowel pin 38 is placed in the openings 18 and 36 and a socket plug 46 of expandable material is placed at each end of the dowel. A number of transload units are assembled in similar manner along the length of the joint, it being understood that the joint filler 10 is provided with spaced apart holes 48 to permit passage of the dowel pin 38 and openings 50 and 52 to permit passage of the cam lips 20 and 22. The concrete slabs 4 and 6 are then poured.

The transload device may also be used in a contraction joint as shown in Figures 8 and 9. The contraction joint differs from an expansion joint in that no filler member is used and a transload device 12' is embedded directly within the concrete with a notched portion 60 being formed in the top face of the concrete directly above the transload elements. If undue stresses are applied to the concrete, such as by overloading or if excessive contraction and expansion takes place, the concrete will relieve these stresses by cracking at the point where the recesses were made, thus forming two separate slabs which are then reinforced by the presence of the transload device. The only difference between the transload device used with the contraction joint and that used with the expansion joint is that the cam lips will extend the same distance from each side of the upright 16 since no filler is used. This is best shown in Figure 9 where it is seen that the cam lips 20' and 22' extend the same distance from each side of the upright 16. The joint is otherwise the same as the expansion joint and the same reference characters are used to indicate corresponding parts. In some instances the cam surfaces on one side of upright 16 are omitted and all of the cam action is done by means of the cam surfaces on one side only.

While two embodiments of our invention have been shown and described, it will be apparent that other adaptations and modifications may be made without departing from the scope of the following claims.

We claim:

1. A transload device for expansion joints between slabs comprising a single vertical plate member, a filler extending along said vertical plate member, said filler and plate member having coaxial holes therethrough, a plurality of spaced apart cam lips extending outwardly from each side of the plate member, said filler having openings therein for passage of the cam lips on that side of the plate member adjacent the filler, a cam surface facing said plate member on each cam lip, a dowel socket on each side of the filler and plate member assembly, each of said sockets having an axial opening therein, cam faced flanges on the inner end of each socket engaging the adjacent cam surfaces on the cam lips to lock the socket in place between said plate member and cam surfaces, and a dowel pin in the openings in said sockets extending through the axial holes in said filler and plate member.

2. A transload device for expansion joints between slabs comprising a single vertical plate member, a filler extending along said vertical plate member, said filler and plate member having coaxial holes therethrough, a plurality of spaced apart cam lips extending outwardly from each side of the plate member, said filler having openings therein for passage of the cam lips on that side of the plate member adjacent the filler, a cam surface facing said plate member on each cam lip, a dowel socket on each side of the filler and plate member assembly, each of said sockets having an axial opening therethrough, cam faced flanges on the inner end of each socket engaging the adjacent cam surface on the cam lips to lock the socket in place between said plate member and cam surfaces, a dowel pin in the openings in said sockets extending through the axial holes in said filler and plate member, an expansible plug in the socket openings at each end of the dowel pin, and horizontal bearing surfaces extending from said socket.

3. A transload device for expansion joints between slabs comprising a support having an inverted T-shaped transverse section, said support having a single vertical plate member, a filler supported on the base of the support and extending along the vertical plate member, said filler and plate member having coaxial holes therethrough, a pair of spaced apart cam lips extending outwardly from each side of the plate member, said filler having openings therein for passage of the cam lips on the side adjacent the plate member, a cam surface on each cam lip, a dowel socket on each side of the filler and support assembly, each of said sockets having an axial opening therein, a pair of cam faced flanges on the inner end of each socket engaging the adjacent cam surfaces on the cam lips to lock the socket in place between said plate member and said cam lips, and a dowel pin in the openings of said sockets extending through the axial holes in said filler and vertical member.

4. A transload device for expansion joints between slabs comprising a support having an inverted T-shaped transverse section, said support having a single vertical plate member, a filler supported on the base of the support and extending along the vertical plate member, said filler and plate member having coaxial holes there-

through, a pair of spaced apart cam lips extending outwardly from each side of the plate member, said filler having openings therein for passage of the cam lips on the side adjacent the plate member, a cam surface on each cam lip, a dowel socket on each side of the filler and support assembly, each of said sockets having an axial opening therethrough, a pair of cam faced flanges on the inner end of each socket engaging the adjacent cam surfaces on the cam lips to lock the socket in place between said plate member and said cam lips, a dowel pin in the openings of said sockets extending through the axial holes in said filler and vertical member, an expansible plug in the socket openings at each end of the dowel pin, and horizontal bearing surfaces extending from said socket.

5. A transload device for transferring loads between adjacent slabs comprising a single vertical plate member, said plate member having a hole therethrough, a plurality of cam lips extending outwardly from each side of the plate member, a cam surface on each of said cam lips, a dowel socket on each side of the plate member, each of said sockets having an axial opening therein, a plurality of cam faced flanges on the inner end of each socket engaging the adjacent cam surfaces on the plate member to lock the socket in place between the cam lips and the plate member, and a dowel pin in the openings of said sockets extending through the opening of said vertical member.

6. A transload device for transferring loads between adjacent slabs comprising a single vertical plate member, said plate member having a hole therethrough, a plurality of cam lips extending outwardly from each side of the plate member, a cam surface on each of said cam lips, a dowel socket on each side of the plate member, each of said sockets having an axial opening therethrough, a plurality of cam faced flanges on the inner end of each socket engaging the adjacent cam surfaces on the plate member to lock the socket in place between the cam lips and the plate member, a dowel pin in the openings of said sockets extending through the opening of said vertical member, an expansible plug in the socket openings at each end of the dowel pin, and horizontal bearing surfaces extending from said socket.

7. A transload device for transferring loads between adjacent slabs comprising a support having an inverted T-shaped transverse section, said support having a single vertical leg, said vertical leg having a hole therethrough, a pair of spaced apart cam lips on each side of the vertical member, a cam surface on each cam lip, a dowel socket on each side of the vertical member, each of said sockets having an axial opening therein, a pair of cam faced flanges on the inner end of each socket engaging the adjacent cam surfaces on the vertical member to lock the socket in place between the cam lips and the vertical member, and a dowel pin in the openings of said sockets extending through the opening in said support.

8. A transload device for transferring loads between adjacent slabs comprising a support having an inverted T-shaped transverse section, said support having a single vertical leg, said vertical leg having a hole therethrough, a pair of spaced apart cam lips on each side of the vertical member, a cam surface on each cam lip, a dowel socket on each side of the vertical member, each of said sockets having an axial opening therethrough, a pair of cam faced flanges on the inner end of each

socket engaging the adjacent cam surfaces on the vertical member to lock the socket in place between the cam lips and the vertical member, a dowel pin in the openings of said sockets extending through the opening in said support, an expandable plug in the socket openings at each end of the dowel pin, and horizontal bearing surfaces extending from said socket.

9. A transload device for expansion joints between slabs comprising a single vertical plate member, a filler extending along said vertical plate member, said filler and plate member having coaxial holes therethrough, a dowel socket on one side of the filler and plate member assembly, said socket having an axial opening therein, means for fastening the socket to the plate member, said means including a plurality of spaced apart cam lips extending outwardly from one side of the plate member, a cam surface on each of said cam lips, cam faced flanges on the inner end of said socket engaging the adjacent cam surfaces to lock the socket in place between said plate member and said cam lips, and a dowel pin in the opening of said socket extending through the hole in said filler and plate member.

10. A transload device for transferring loads between adjacent slabs comprising a single ver-

tical plate member, said plate member having a hole therethrough, a dowel socket on one side of the plate member, said socket having an axial opening therein, means for fastening the socket to the plate member, said means including a plurality of spaced apart cam lips extending outwardly from one side of the plate member, a cam surface on each of said cam lips, cam faced flanges on the inner end of said socket engaging the adjacent cam surfaces to lock the socket in place between said plate member and said cam lips, and a dowel pin in the opening of said socket extending through the hole in said plate member.
